(57) **CLAIM**

The ornamental design for a bread pan, as shown and described.

DESCRIPTION

FIG. 1 is a view in perspective of a bread pan as seen from the top and two sides showing my new design;

FIG. 2 is a view in perspective as seen from the bottom and two sides;

FIG. 3 is a view in top plan;

FIG. 4 is a side elevation as seen from bottom to top of FIG. 3;

FIG. 5 is a side elevation as seen from the side opposite that shown in FIG. 4;

FIG. 6 is a side elevation as seen from right to left of FIG. 5;

FIG. 7 is a side elevation as seen from the side opposite that shown in FIG. 5; and

FIG. 8 is a bottom plan;

FIG. 9 is a view in perspective of an alternate bread pan as seen from the top and two sides;

FIG. 10 is a view in perspective as seen from the bottom and two sides;

FIG. 11 is a view in top plan;

FIG. 12 is a side elevation as seen from bottom to top of FIG. 11;

FIG. 13 is a side elevation as seen from the side opposite that shown in FIG. 12;

FIG. 14 is a side elevation as seen from right to left of FIG. 13;

FIG. 15 is a side elevation as seen from the side opposite that shown in FIG. 13; and,

FIG. 16 is a bottom plan.

The broken line showing of a bread machine interface shown in FIGS. 9, 10 and 12–16 are for illustrative purposes only and forms no part of my claimed design.

1 Claim, 8 Drawing Sheets
